TORSION BALANCE

Erich Reeh, Hanover, Germany

Application October 9, 1936, Serial No. 104,869
In Germany August 13, 1935

1 Claim. (Cl. 265—1.5)

This invention relates to improvements in torsion balances.

The exactness of measurements obtained by means of the usual torsion balances is injured by 5 different phenomena, chiefly by variations of temperature which occur during the measuring operation and whereby air currents are produced.

In order to insure the measurements against the influence of variations of temperature caused 10 by air currents the proposal has been made to surround the pendant with a number of thin-walled metallic boxes or pipes which in turn are separated from one another by air spaces and are not connected by metallic material.

15 Attempts were made to make the casing of a bad conductor of heat, but it was found that such materials are not uniformly heated so that the inner walls show marked differences in temperature.

20 According to the present invention the pendant is disposed in a metallic casing the walls of which have a thickness substantially equal to or greater than the diameter of the space in which the oscillation takes place.

25 Whereas the most sensible of the usual torsion balances are subject to an average error of about 0.5 arc minute in adjusting the beam, this error may be reduced to 0.11 arc minute by disposing the pendant according to the present invention 30 in a metallic casing the walls of which have a thickness of about 1.7 times the diameter of the space of oscillation.

The invention is based on the discovery that 35 the flow of heat in the interior of a thick wall is more uniform than that in a thin wall.

Moreover it was found that the damping can be varied by inserting thin-walled tubes fitting 40 into one another so as to touch one another with their inner and outer surfaces, the flow of heat from metal to metal not being impeded. More or fewer of these tubes may be removed to vary the width of the space where the oscillation takes place, thereby also varying the degree of damping.

45 damping.

The invention is illustrated by way of example in the annexed drawing of which

Fig. 1 shows a longitudinal cross-section of a casing including the pendant, and Fig. 2 is a cross-section on the line A—B of Fig. 1. 5

a is the torsion wire, b a mirror connected with the pendant, c the carrier of the cross-beam. d designates the beam of the balance, at the ends of which are secured the heavy bodies e, e. f is the casing surrounding the space of oscillation g. h is a tube fitting into the casing. 10

Owing to the reduction of the error of adjustment according to the present invention it is also possible to shorten the time of calming down 15 by diminishing the moment of inertia and increasing the coefficient of torsion. In this case the sensibility of 1.10^{-9} dyn per 0.01 cm. of deflection may be retained whilst considerably reducing the time of calming down.

For making the casing, preferably a metal of 20 good heat conductivity is chosen, as, for instance, copper, phosphor bronze, aluminum or silver. Aluminum is particularly adapted for the purpose of the invention because when using it the weight of the torsion balance is not considerably increased as compared with the weight of 25 the usual torsion balances.

The specific heat of the metal employed likewise influences the balances made in accordance with the invention inasmuch as by absorbing 30 or withdrawing a certain quantity of heat the temperature is only moderately affected in case the specific heat of the material of the casing is high.

In this respect again aluminum is very well 35 qualified owing to its high specific heat.

I claim:—

A torsion balance comprising a pendant including a cross beam and a supporting filament 40 therefor, a homogeneous casing of high heat conductivity enveloping said balance, the thickness of said casing at least approximating the diameter of the space provided therein for oscillation of said beam. 45
